UNITED STATES PATENT OFFICE.

EDWARD M. WARING, OF NEW YORK, N. Y.

SUCTION CLEANING APPARATUS.

1,105,942.

Specification of Letters Patent.

Patented Aug. 4, 1914.

Application filed March 16, 1909. Serial No. 483,844.

To all whom it may concern:

Be it known that I, EDWARD M. WARING, a citizen of the United States of America, and a resident of the borough of Brooklyn, 5 city, county, and State of New York, have invented certain new and useful Improvements in Suction Cleaning Apparatus, of which the following is a specification.

This invention relates to suction cleaning 10 devices and has particular reference to a portable device adapted to be operated by the foot power of the operator. This may be done either while the operator remains at one spot or when the operator is walking 15 about cleaning a room. An apparatus of this kind presents the advantage that the operation thereof happens wholly instinctively, so to speak, and the operator is at liberty to give the entire attention to the 20 handling of the cleaning nozzle and to the object to be cleaned.

In order to accomplish its objects the invention comprises a suction mechanism adapted to be operated by the foot power 25 of the operator, and to the said mechanism a suitable cleaning nozzle is attached by means of a flexible hose.

The invention also comprises an improved form of nozzle.

30 The following specification and the drawing illustrate this invention in its preferred form but changes may of course be made without departing from the scope of the invention.

35 In the said drawing Figure 1 is a general view illustrating the mode of using the cleaner. Fig. 2 is a view, partly in section and partly in perspective, of a cleaning device embodying my invention. Figs. 3 and 40 4 are detail views of two forms of dust bags. Figs. 5 and 6 are detail views in section of the suction boxes in two different positions. Fig. 7 shows a modified form of suction box. Fig. 8 is a sectional view of a nozzle attached 45 to a carpet sweeping device.

Referring more particularly to Figs. 2, 5 and 6 the reference numerals 1 and 2 denote the suction boxes, which are alike and each of which comprises a bottom 3 and top 4 connected together by a collapsible or bellows section 5 making an air tight box. The interior of the box communicates at one end with the atmosphere through a valve 6, which only opens outwardly. At the other

end the top 4 carries a short tube 7 the bottom of which is closed air tight by a valve 8 which only opens inwardly. Speaking with reference to the atmosphere the valve 8 may be called the intake valve and the valve 6 the outlet valve, as will hereinafter be explained. As the box is inflated and deflated the top 4 moves up and down and during its movement it is guided by pins 9 fast in the bottom. Spring 10 coiled around the pins assist in the upward movement of the top. A feature of these suction boxes is, as shown in Figs. 5 and 6, that the bottom and the top are provided with beveled portions 11 and 12 so that when the box is deflated the folded parts of the bellows 5 fits 70 between the beveled portions and thus the top may be brought close down on the bottom. In this manner all the air is forced out of the box for each downward movement of the top and a powerful suction is 75 obtained.

If desired, rubber buttons 13 may be provided on the bottom, and at the top there is fastened adjustable toe and instep straps 14 and 15 respectively for fastening the boxes 80 to the feet of the operator.

The two boxes are joined to a Y-connection 16 by means of two slightly yieldable hose 17, 17 which fit over the aforesaid tubes 7 and the third mouth of the Y is connected 85 to the nozzle 21 by the flexible hose 18, which latter may be carried over the shoulder as shown in Fig. 1 or a strap 19 with a loop 20 may be used for carrying the hose 18. The nozzle 21 in this instance comprises 90 the mouth 22 of any suitable shape or form, the enlarged connection 23 containing the dust bag and the hollow handle 24. The bag chamber within the connection 23 contains the dust catching bag 25 which is fastened 95 to the mouth by a threaded connection 26 and it will be observed that all the parts of the nozzle are screwed together for the purpose of being easily taken apart for cleaning.

100 The dust bag may be made of cheese cloth or similar porous material, permitting passage of the air but retaining the dust. Fig. 3 shows a bag 27 attached to the threaded connection 28 by a flexible slip ring 29, while 105 the bottom 30 of the bag is solid and attached to the bag by a similar ring 31. In Fig. 4 the bag 32 is simply tied to the con-

nection 33 and closed with a drawstring 34. Thus the bag may be entirely removed and washed.

Fig. 7 shows a suction box 35 in which 5 moves a piston 36 provided with valves as above described. In this instance the guide pins 37 with the springs 38 are inside the box, which latter is preferably made oval in form. The boxes 1 and 2 may also be made 10 oval if desired and this form is shown on Fig. 1.

In Fig. 8 the numeral 39 designate a carpet sweeper built on the usual lines. Adjacent the rotating brush 40 I provide a nozzle 15 41 of any suitable form and constructed similar to the nozzle 21. In this instance the brush 40 sweeps the dust up in addition to the sucking action of the nozzle.

The operation of the device is as follows: 20 The operator straps the two boxes to her feet, and adjusts the hose 18 so as to leave her arms and hands free to handle the nozzle. If the operator remains on one spot for a while the sucking action of the boxes 25 is produced by a rocking motion by the alternate lifting of the feet if the operator moves about the sucking action is produced by the natural lifting and stepping down with the feet in walking. When the top, 4 30 of the box is pressed down, the air in the box escapes through the valve 6 after which said valve is kept closed by the atmospheric pressure. When the weight of the operator's 35 body is removed from the box, the top 4 is forced upward by the springs 10. In this

manner a powerful suction is created at the nozzle mouth 22, the dust is sucked up and caught in the dust bag.

The advantages of this invention are these that the operator produces the suction by 40 the natural movements of the feet in walking either on the spot or when moving about while attending to the work of handling the nozzle and without any special effort. Further the suction is more powerful than if it 45 is produced by hand power. The hose 18 may of course be lengthened and another person than the operator work the suction boxes. The details of the construction may of course be modified without departing 50 from the scope of the invention and I am not to be understood as confining myself to the exact form shown.

I claim:

The combination of a pair of independent 55 bellows adapted to be secured severally to the feet of an operator whereby they may be moved from place to place while being operated, flexible piping connecting the suction inlets of the bellows, and a suction pipe connected to the said flexible piping at an intermediate point of the length thereof whereby a continuous inflow will be established through the suction pipe.

Signed at New York, N. Y., this 9 day of 65 March, 1909.

EDWARD M. WARING.
